METALLIC TIE FOR TRACK RAILS

James H. Keith, Cleveland, Ohio

Application April 19, 1944, Serial No. 531,751

3 Claims. (Cl. 238—183)

This invention relates to track rail supporting and holding means and has for its general object to provide an improved metallic tie adapted to receive and support the meeting ends of longitudinally aligned track rails, the tie being provided with improved locking means for separably uniting the rails in secure relation with the tie, whereby to hold effectively the rails in track-forming order.

It is another object of the invention to provide a rail-holding tie adapted particularly for the support and uniting of rails used in forming extension, emergency or auxiliary trackways, and wherein provision is made for quickly and securely uniting rails with the tie without involving the use of customary threaded bolts, nuts or spikes.

In coal mines, as well as in many other capacities, it is often necessary for tracks to be extended quickly to follow retreating mining faces. To expedite such an operation, it is inconvenient and too time-consuming to spike the rails to permanent wood ties and connecting the meeting ends of rail sections with the conventional fish plates, bolts and nuts.

Accordingly, the present invention provides a metallic tie especially adapted for the rapid laying of extension tracks of the character indicated, the construction of the tie being such as to facilitate the operation of connecting track rails therewith in order that there need be but little delay in extending a given trackway to a desired working location.

For a further understanding of the invention, reference is to be had to the following description and the accompanying drawing, wherein:

Fig. 1 is a top plan view of a metallic rail tie formed in accordance with the present invention;

Fig. 2 is a similar view on a larger scale, with parts broken away and shown in horizontal cross section;

Fig. 3 is a vertical transverse sectional view taken on the plane indicated by the line III—III of Fig. 2;

Fig. 4 is a perspective view of one of the inner clamping plates;

Fig. 5 is a similar view of an outer clamping plate;

Fig. 6 is a detail perspective view of one of the splice bars.

In accordance with the present invention, I provide a metallic tie, indicated by the numeral 10. In its preferred embodiment, the tie is formed to comprise a flat horizontally disposed body 11 which terminates at its sides in down-turned,

longitudinally extending and parallel flanges 12, which are capable of exerting a firm grip on the floor of a mine or to occupy a stable position in ballast when the latter is used. As a practical matter, I prefer to form the tie from rolled steel plate. The tie is adapted to be placed beneath conventional track rails 13 and particularly beneath the meeting ends of a pair of longitudinally aligned rails, in order to provide for the support of such rails and unite the same to the tie and with each other. To effect this result, the upper surface of the tie is provided at each end thereof with rail-clamping or fish plates 14 and 15, respectively, the latter being stamped from steel plate having approximately the same thickness as the plate from which the tie is formed.

Each of the outer plates 15 comprises a flat horizontally disposed body portion 16 positioned for longitudinal adjustment on the upper surface of the tie 10. To provide for such adjustment, the body portion 16 is provided with headed pins or loose rivets 17, the shanks of which are received in elongated slots 18 formed in the body 11 of the tie 10. At its outer edge, each of the plates 15 is provided with a short upstanding flange 19, and at the sides thereof with vertical flanges 20, the inner edge portions of the latter terminating in lugs 21, which are receivable in openings 22 provided in splice bars 23. These bars span the meeting ends or faces of a pair of the rails 13, and at their ends the bars 23 terminate in inwardly directed studs 24, which are adapted to be positioned in the usual bolt openings 25 formed in the vertical webs 26 of the rails 13, the splice bars serving to prevent undue longitudinal separation of an aligned and adjoining pair of rails.

Riveted for turning movement about vertical axes provided by rivets 27 carried by the outer ends of the tie 10 are turnable securing cleats 28. These cleats are also formed from stamped metallic plate and each of the cleats has its ends upwardly and angularly directed as at 29 for engagement with the flanges 19 of the plates 15, the upturned ends 29 of said cleats being arcuate in plan. It will be seen that when the splice bar 23 is positioned in the openings 25 of the rails 13, and the outer plate 15 moved longitudinally of the tie so that its lugs 21 are positioned in the openings 22, these parts may be locked in their rail fastening positions by turning the cleats 28, usually effected by a hammer or sledge, until a firm union is secured.

Likewise, the inner clamping or fish plates are each formed to provide a plate-like body 30 which,

contiguous to the rails 13, has an integral offset extension 31 shaped to engage and lap over the base flange 32 of said rails as well as engage the inner surfaces of the webs 26 thereof. At the juncture of the body 30 with the extension 31, there is formed a shoulder 33 adapted for position maintaining engagement with the inner vertical edge of the base flange of the associated rail or rails. Similar engagement is maintained between the outer edges of the base flanges of said rails and the inner edges of the body portion 16 of the plates 15.

The inner of the plates 14 have their body portions 30 provided with depending rivets 34 whose shanks are loosely positioned for sliding movement in slots 35 formed in the tie body 11. To maintain the extensions 31 of the inner plates in desired holding engagement with the rails 13, each of the plates 14 has its inner end terminated in an upstanding lip 36 with which is engaged a turnable cleat 37 riveted, as at 38, to the tie body 11. By rotating the cleat so that it is longitudinally aligned with its complementary plate 14, as in Fig. 2, the same will serve to hold the associated plate in firm position-maintaining engagement with the track rails.

It will thus be apparent that the present invention provides a tie particularly useful in the extension of track rails to various working locations, as in coal-mining operations. In coal mining, considerable use is made of track-mounted machines, such as coal-cutting and loading machines. As the working face of a coal seam recedes through mining operations, it is necessary to advance the trackway proportionately, so that the machines may be terminated in proper relation to the working face.

With the use of the tie forming the present invention, extension tracks may be quickly laid, and this may be done without the use of threaded fastening members. It frequently happens that such extension trackways are covered with water, and my improved tie has been constructed so that rails may be readily secured therewith even under such adverse conditions, it merely being necessary to rotate the holding or locking cleats shown at 28 and 37. Furthermore, the construction provides for proper electrical binding between adjacent rail sections, as many mining machines are electrically driven and utilize the track rails as return conductors. It will be noted that the construction of my improved tie is essentially simple and may be produced from materials which are generally available at mining sites, enabling repairs and replacements, when needed, to be readily furnished.

I claim:

1. Rail-holding means for extension trackways, comprising a metallic tie having down-turned side flanges and a flat upper surface for the reception of the base flanges of track rails, a pair of inner and outer rail-clamping plates slidably secured to said tie at each end thereof for limited longitudinal adjustment, said inner plates being each formed with offset extensions shaped to engage

5 the base flanges and vertical webs of the track rails, said outer plates having position-maintaining engagement with the base flanges of said rails and having vertical side flanges terminating in inwardly and horizontally projecting lugs, a splice bar spanning the meeting faces of a pair of said track rails and formed at its ends with laterally and inwardly directed studs receivable in bolt openings provided in the vertical webs of the adjusting rails, said bar being provided with spaced sockets for the reception of the outer plate lugs, and turnable cleats mounted on the upper surfaces of said tie and movable into engagement with the ends of said plates to maintain the latter in positive fastening and holding engagement with said rails.

2. Splice means for uniting the meeting ends of a pair of track rails comprising a tie adapted to be placed beneath the meeting ends of a pair of such rails, an outer rail-clamping plate slidably mounted for limited longitudinal adjustment on the upper surface of said tie, said plate having position-maintaining engagement with the base flanges of said rails and being formed with vertical side flanges which terminate in inwardly and horizontally projecting lugs, a splice bar spanning the meeting faces of said track rails, said bar being formed at its ends with laterally and inwardly directed studs receivable in bolt openings provided in the vertical webs of the adjoining rails, said bar being provided with spaced sockets for the reception of the plate lugs, and turnable cleats mounted on the upper surface of said tie and movable into and out of engagement with the outer end of said plate to maintain and withdraw the latter from holding engagement with said rails and splice bar.

3. Rail-holding means for extension trackways comprising a metallic tie having a flat upper surface for the reception of the base flanges of track rails, a pair of inner and outer metallic rail-clamping plates positioned on the upper surface of said tie at each end thereof, fastening elements carried by said plates having shanks slidably positioned in slots provided longitudinally in said tie, said inner plates being formed with offset extensions shaped to engage the base flange of said rails, said outer plates having edge engagement with the base flanges of said rails, said outer plates embodying vertical side flanges terminating in inwardly and horizontally projecting lugs, splice bars spanning the meeting faces of adjoining track rails and formed at the ends thereof with laterally and inwardly directed studs receivable in bolt openings provided in the vertical webs of adjoining rails, said bars being formed with spaced sockets for the reception of the plate lugs, and pivoted cleats mounted on the upper surfaces of said tie, said cleats being movable into and out of engagement with the ends of said plates to maintain and remove the latter in and from positions of holding engagement with said rails.

JAMES H. KEITH.
